Company, a corporation of DelawareFiled Dec. 15, 1961, Ser. No. 159,645
8 Claims. (Cl. 200—61.53)

The present invention relates to vibration responsive means and more particularly to a vibration responsive switch.

Briefly, this device is a normally closed switch, which when subjected to linear vibrations of a given frequency and amplitude, breaks an electrical circuit and accordingly one object of the present invention is to provide a means of sensing vibrations of a given magnitude and frequency.

Another object is to provide a switch for controlling an electrical circuit by maintaining the circuit closed below a preset level of vibrations.

Still another object is to provide a switch for opening and maintaining an electric circuit open by vibrations above a preset level.

Yet another object is to provide a vibration switch device used to open or close a circuit directly without the use of capacitors and/or relays.

Other objects and advantages of the invention will become apparent in the course of the following detailed description, taken in connection with the accompanying drawing, wherein:

FIGURE 1 illustrates one form of the present invention in longitudinal cross section; and

FIGURE 2 is a top plan view of the same.

Referring in detail to the drawing and first with particular reference to FIGURE 1, the present novel device consists of a casing 10, which is preferably cylindrical. Within the casing cylinder 10 is a mass member, such as a piston 11 and a coil compression spring 12, which spring has the lower convolution 14 thereof engaged with the flat top surface of the piston 11 and the upper convolution 15 thereof engaged against a plate 16 formed with a central bleed port 17.

The casing cylinder 10 is counterbored at its respective lower and upper ends to provide an annular shoulder 19 at the lower end and an annular shoulder 20 at the upper end. For example, the lower end of the cylinder is sealed closed by a disc 22 which seats on the shoulder 19 and is held in place by staking or turning over the peripheral rim of the lower counterbored portion of the cylinder.

The disc 22 is formed of suitable insulating material and is centrally formed with an air exhaust port 23. Also, the disc 22 serves as a support for electric contacts or jacks 24 and 25.

Directly above the interior side of the disc 22 in the casing 10 is a dish-shaped disc 27 formed of suitable conducting material adapted to engage and disengage with the electric contacts 24 and 25 responsive to preset vibration levels received in the device.

The dish-shaped disc 27 is formed with a center opening and is depended from the flat surfaced lower end of the piston 11 by means of a concentrically mounted depending stud 28, which is formed with a head 29 to retain an insulated eyelet 30. The eyelet fits in the opening of the disc 27 and also on the stud above the disc 27 the stud carries an arcuate washer 30a, whereby the contact disc 27 is mounted to wobble about the fixed center point provided by the stud.

The casing 10 at the upper counterbored end confines therein the spring engaging plate 16, which seats on the annular shoulder 20. The plate 16 is held against the shoulder 20 by an end cap 31. The end cap 31 is cup-shaped and is cupped downwardly so the rim 32 of the

2

cup clamps the peripheral rim surface of a diaphragm 33 between said rim and the underlying peripheral surface of the upper side of the spring plate 16. The diaphragm on one-way valve means 33 includes an upstanding bead 35 formed with ports 36 and is responsive to pressure from within the spring chamber 34 in the casing 10 above the piston 11. The diaphragm flexes to open and close the central opening or port 17 in the spring plate 16. When the diaphragm serves as a one-way valve means and is moved to open position by air compressed in the chamber 34, air then bleeds from the chamber through opening 17 and diaphragm ports 36 to atmosphere through an exhaust port 37, in the cap 31.

The bore of the cylinder 10 is slightly larger than the circumference of the piston 11 to provide a clearance therebetween, such as an annular air gap 31 between it and the cylinder bore for the purpose hereinafter explained. As above described there is provided a chamber 34 above the piston 11, and also there is a chamber 39 below the piston 11, which chamber exhausts through port 23 at low level vibrations to close the switch contacts as will be explained hereinafter in detail under the heading "Operation."

Operation

The contacts 24 and 25 are connected to a suitable electric circuit, which are normally bridged to switch closed position by the conducting disc 27 when the switch is at rest. For example, when the switch is at rest compression spring 12 forces piston 11 to the extreme downward switch closed position.

If the switch device is subjected to vibrations along the longitudinal axis of casing 10, of sufficient magnitude and frequency to overcome the force of compression spring 12, the piston 11 oscillates within the casing 10. During the resulting upward stroke of the piston 11, air is drawn into lower chamber 39 through port 23. The air in upper chamber 34 is compressed until the pressure is sufficient to move diaphragm 33 away from port 17. Air then bleeds from upper chamber 34, through port 17, and diaphragm ports 36 to atmosphere through exhaust port 37.

Air continues to exhaust to atmosphere until the piston 11 reaches maximum height for a preset vibration level condition and the pressure in upper chamber 34 approaches atmospheric pressure. The diaphragm 33 then returns and closes port 17.

On the downward stroke of the piston 11, air in the lower chamber 39 is exhausted through port 23 to atmosphere, and air in upper chamber 34 drops below atmospheric pressure. The resulting differential pressure between upper and lower chambers 34 and 39 impedes further displacement of the piston 11.

One period of the excited force is thus completed before the piston 11 reaches the extreme lower switch closed position. It can be seen that during continued vibration responsive oscillations of the piston 11 within the casing 10, the conducting disc 27 never touches the contacts 24 and 25. The external circuit connected across contacts 24 and 25 is, therefore, maintained in an open position. When the external vibrations cease the force of compression spring 12 on piston 11 is opposed by the differential pressure existing between chambers 34 and 39.

Air from chamber 39 slowly bleeds through clearance 31, into upper chamber 34. This action decreases the differential pressure across piston 11, and the compression spring 12, returns piston 11 to the extreme lower position, permitting conducting disc 27 to touch contacts 24 and 25, thereby closing the electrical circuit.

The preset level of the present novel device can be varied, if desired, by changing the mass of piston 11, the strength of the compression spring 12 and/or the respon-

sive action of the pressure diode on one-way valve 33 by varying the bleed port size. Thus any adjustment in the spring rate, weight of the piston, or both will cause the break point, G-level, of the switch to change, making it possible to employ this device to sense vibrations at any frequency.

Also, a delay on make of the switch can be controlled by varying the clearance 31.

If desired, the entire unit may be hermetically sealed by encapsulation with a suitable dielectric material, provided there is an air path between port 23 and port 37, external to the casing 10.

Without further description it is believed that the advantages of the present invention over the prior art is apparent and while only one embodiment of the same is illustrated, it is to be expressly understood that the same is not limited thereto a various changes may be made in the combination and arrangement of the parts illustrated, as will now likely appear to others and those skilled in the art. For a definition of the scope or limits of the invention, reference should be had to the appended claims.

What is claimed is:

1. A normally closed switch for controlling an electrical circuit comprising a casing, a piston means oscillatable in the casing in response to preset levels of vibration, said piston carrying a switch conductor means, spring means biasing said piston and switch conductor means to closed circuit position, said piston dividing said casing into upper and lower chambers, said casing having an opening in the lower end thereof communicating with said lower chamber, and said casing having a diaphragm controlled exhaust valve in the upper chamber movable to open position by air compressed in said upper chamber.

2. Means responsive to preset vibration levels comprising a casing, electric contact means in the lower end of the casing, a movable mass in said casing, electric switch means secured to the lower side of said mass, a compression spring engaged with the upper side of said mass and seated in the upper end of said casing normally biasing said mass to the circuit closing position of said switch means below said preset vibration levels, and one-way valve means mounted in the upper end of said casing above said spring for bleeding air in response to air compressed in said upper end of the casing by the upward switch open position of said mass in response to said preset vibration levels.

3. Means responsive to preset vibration levels as described in claim 2, wherein said casing is a cylinder and said mass is a piston.

4. Means responsive to preset vibration levels as described in claim 2, wherein said mass is relatively smaller in circumference than the interior bore of said casing to provide clearance therebetween for passage of air to thereby delay the return of said mass by said spring to the normal switch closing position thereof.

5. A normally closed vibration responsive switch comprising a casing, a movable mass in said casing dividing

5 said casing into upper and lower chambers, a compression spring in the upper chamber biasing said mass toward the bottom of said lower chamber, circuit-connecting contacts at the bottom of said lower chamber, contact closing means carried by said mass in said lower chamber and engageable with said contacts, said lower chamber being closed at its lower end by an insulated disc for supporting said contacts, said disc having an air opening therein, and said upper chamber of the casing being provided with a one-way valve means actuated in response to the air compressed in the upper chamber resulting from the movement of said mass.

6. The vibration responsive switch described in claim 5, wherein said one-way valve means comprises a centrally apertured plate, a flexible diaphragm with openings therein movable to open and close the central aperture in the plate, and an end retainer cap with an opening therein, said cap retaining said diaphragm in operative position, whereby movement of said mass to open switch position varies the pressure of the air in said upper chamber to raise said diaphragm above said plate aperture, to thereby bleed air to atmosphere through said diaphragm openings and draw air into said lower chamber through said air opening in said disc.

7. A normally closed switch responsive to linear vibrations of a preset frequency and amplitude, comprising a casing, means responsive to said vibrations to open said switch, and bias means for said vibration responsive means to maintain said switch closed against vibrations below said vibrations of preset frequency and amplitude, said switch including a dish-shaped disc of conducting material, a pair of spaced contacts mounted in the bottom of the casing, said disc being loosely mounted in the lower portion of said vibration responsive means on an insulated stud, whereby the said disc is free to wobble about the fixation point provided by said stud and one-way pressure operated valve means at an end of the casing, to thereby bleed air to the atmosphere.

8. A normally closed electric switch responsive to vibrations above a preset level comprising a cylinder, a piston in said cylinder, said piston being movable by linear vibrations along the longitudinal axis of said cylinder, pneumatically actuated one-way valve means responsive to the movement of said piston, variable spring means controlling the vibration response level of said piston, conductor means carried by said piston, and spaced electric contact members mounted in the lower end of said cylinder connected by said conductor means in the normally closed position of the switch.
